US0D1114175S

(12) **United States Design Patent** (10) Patent No.: **US D1,114,175 S**
(45) Date of Patent: ** Feb. 17, 2026

(54) **ADAPTER FOR FAUCET AERATOR**

(71) Applicant: **Neoperl GmbH**, Müllheim (DE)

(72) Inventors: **Sascha Horoba**, Gottenheim (DE);
David Birmelin, Müllheim (DE)

(73) Assignee: **Neoperl GmbH**, Müllheim (DE)

(**) Term: **15 Years**

(21) Appl. No.: **35/523,042**

(22) Filed: **Aug. 5, 2024**

(80) **Hague Agreement Data**

Int. Filing Date: **Aug. 5, 2024**

Int. Reg. No.: **DM/241930**

Int. Reg. Date: **Aug. 5, 2024**

Int. Reg. Pub. Date: **Nov. 22, 2024**

(51) **LOC (15) Cl.** **23-01**

(52) **U.S. Cl.**

USPC **D23/229**; D8/21

(58) **Field of Classification Search**

USPC D23/200, 213, 223, 228, 229, 230;

(57) **CLAIM**

The ornamental design for an adapter for a faucet aerator as shown and described.

DESCRIPTION

1. Adapter for faucet aerator

1.1 : Top

1.2 : Bottom

1.3 : Back

1.4 : Front

1.5 : Right

1.6 : Left

1.7 : Perspective

1.8 : Perspective

1.9 : Perspective

1.10 : Perspective

1 Claim, 10 Drawing Sheets
